UNITED STATES PATENT OFFICE.

GEORGE W. DOVER, OF PROVIDENCE, RHODE ISLAND.

CURTAIN-SUPPORTING STRUCTURE.

Application filed October 6, 1925. Serial No. 60,756.

This invention relates to an improved curtain supporting structure for supporting lace curtains and draperies to positively hold them in position across the window, while enabling the curtains to be turned from in front of the window when desired so that the window may be opened and air admitted freely without the curtains being blown into the room or out the window by the air currents.

One object of the invention is to provide a structure of this character for supporting divided lace curtains and a divided valance in such a manner that the draperies are held in position throughout substantially their entire lengths at all times and so supported as to meet at the center of the window and present the appearance of a single curtain.

Another object of the invention is the provision of vertically adjustable supporting arms which may be readily adjusted to conform to the length of the curtain desired or to compensate for shrinkage of the curtain.

Another object of the invention is to provide weighted means overlying the curtains adapted to retain the free portions of the curtains substantially in normal position and prevent those portions from being blown into the room or out of the window when the window is opened.

A further object of the invention is to provide supporting means for both the top and bottom of a lace curtain which permits the same to be swung bodily into position before the window or out of in front of the window.

Other objects of the invention relate to improved details of construction and methods of operation as will be more fully set forth in the detailed descriptions to follow,

Referring to the drawings:

Fig. 1 is a front view of the structure as applied to a window showing the curtains and draperies in assembled position, with one form of weighted means for holding portions of the curtain against being blown from their normal position.

Fig. 2 is a front view of that part of the curtain supporting structure which is located upon one side of the window,

Fig. 3 is a side elevational view of the structure shown in Fig. 2,

Fig. 4 is a top plan view of the upper curtain supporting members,

Fig. 5 is an enlarged view of the upper

bearing bracket, taken along the line 5—5 of Fig. 3,

Fig. 6 is an enlarged view of the lower bearing bracket, taken along the line 6—6 of Fig. 3,

Fig. 7 is a vertical sectional view of the lace curtain, showing a modified form of weighted means for holding portions of the curtain against being blown out of normal position,

Fig. 8 is a perspective view of the clip employed in connection with that form of weighted member shown in Fig. 1,

Fig. 9 is a detail front view of a lace curtain showing another modified form of weighted member and the supporting means therefor,

Fig. 10 is a detail sectional view taken along the line 10—10 of Fig. 9,

Fig. 11 is an enlarged horizontal sectional view showing the lower drop curtain supporting member, taken along the line 11—11 of Fig. 3,

Fig. 12 is an enlarged horizontal sectional view showing the lower lace curtain supporting member, taken along the line 12—12 of Fig. 3,

Fig. 13 is an enlarged sectional view taken along the line 13—13 of Fig. 2 showing the form of the extension member and supporting member, and,

Fig. 14 is a detail view showing a portion of the drop curtain as seen from the rear and showing the manner in which it is secured to the lower supporting member.

In the embodiment of the invention as shown herewith 1 designates a window frame of conventional type to each side of which are secured upper and lower bearing brackets 2 and 3 respectively for rotatably supporting vertical shafts 4. The upper bearing brackets 2 located on opposite sides of the frame are of similar construction and are each provided with a lug 5 adapted to engage the outer edge of the frame 1 to 100 which the bracket is secured by screw 6. Each of the brackets 2 is bent adjacent its free end to form a bearing 7 for rotatably supporting the shaft 4 and a restricted opening 8, communicating with the bearing 7. 105 In like manner the lower bearing brackets 3 are each provided with a lug 9 adapted to engage the outer edge of the frame 1 to which each bracket is secured by a screw 10. Each bracket 3 is bent to form a bearing 11 110

for rotatably supporting the shaft 4 and a restricted opening 12 communicating with the bearing 11. Each of the lower bearing brackets 3 is provided upon its upper face with depressions 14 for the reception of a pin 15 carried by the shaft 4 whereby the shaft 4 may be movably held in a variety of angular positions.

The shafts 4 upon opposite sides of the window frame are each provided with upper and lower reduced portions 17 and 18 spaced from each other a distance equal to the distance between the corresponding upper and lower bearing brackets 2 and 3, whereby each shaft 4 may be positioned in the bearing brackets by passing the reduced portions through the restricted openings in the upper and lower bearing brackets, whereupon each shaft 4 may be lowered into the position shown in Fig. 3 when it will be supported by the pin 15 resting in one or more of the depressions 14 of the lower bracket 3.

The upper end of each shaft 4 is threaded as shown in Figs. 2 and 3, and provided with a stop nut 20 threaded thereon. Positioned above the nut 20 and adjustably sleeved upon the shaft are a lace curtain supporting member 21, a drop curtain supporting arm 22 and a valance supporting arm 23, while a lock nut 24 is threaded upon the upper end of the shaft above the valance supporting arm 23. The supporting arms 21, 22 and 23 are located one above the other and are each provided with a circular portion sleeved over the shaft 4, a straight shank portion 26, a curved portion 27 and a relatively straight end portion 28, the arrangement of the curved portions being such that the curved and straight end portions of the several arms are offset outwardly from each other from the lowest to the highest.

Each of the arms 21, 22 and 23 are also formed of two parts, the portion carried by the shaft being formed of solid material as indicated at 30 while the end portion 31 is in the form of a sleeve which fits over the straight portion 28 of each arm and projects outwardly therefrom. The sleeve 31 is formed to frictionally engage the solid portion 30 of the arm at the points 32 whereby the sleeve may be drawn out to give the arm the desired length to fit windows of varying width.

The supporting arms 21, 22 and 23 are vertically adjustable upon the shaft 4 by varying the position of the stop nut 20 to properly position the curtains and draperies relative to the top of the window.

The lower lace curtain supporting arms 40 carried by the shafts 4 may be formed as shown in Fig. 12 with duplicate portions 41 and 42, connected by a curved portion 43 surrounding the shaft. A bolt 44 is passed through the duplicate portions 41 and 42 adjacent to the shaft 4 and provided with a

nut 45 whereby the arms 40 may be adjustably secured to the shafts 4 in any one of a plurality of adjusted positions to adapt them for use with windows of varying lengths as well as to permit adjustment due to shrinkage of the curtains. One or both of the duplicate portions 41 and 42 may be provided throughout a portion of their length with curved projections 46 which may be arranged in staggered relation and which serve to engage the curtain fabric interposed between the duplicate portions and firmly hold the same with pleats in the curtains. Extensions 47 may be sleeved over the straight end portions of the duplicate portions 41 and 42 to serve as extensions whereby the supporting arms 40 may be varied in length to fit windows of varying width and the construction of the extensions is preferably the same as that of the sleeves 31 as shown in Fig. 13. A clip 48 is adapted to engage over the free ends of the extensions 47 to clamp the curtains between the duplicate portions of the curtain supporting arm. A sheath 50 of fabric material may be drawn over one or both of the duplicate portions 41 and 42 to cover the metal from view or the metal portions may be enameled if desired.

The lower drop curtain supporting arms 52 may be each formed with a curved portion 53 surrounding the shaft 4 and an end portion 54 positioned in proximity to the straight portion 26, these parts being capable of being drawn together to clamp the arm to the shaft 4 by means of a bolt 55 passed through the portions 54 and 26 and provided with a nut 56 clamping the arm in any desired vertical position on the shaft. The lower drop curtain supporting arms, like the arms 21, 22 and 23 are provided with extension sleeves 31 formed in a similar manner to the sleeves 31 and similarly mounted upon the drop curtain supporting arms.

The curtain supporting structure above described is arranged in duplicate and positioned upon opposite sides of the window frame. Lace curtains 60 are supported by upper and lower lace curtain supporting arms 21 and 40, the upper portion of each curtain 60 being provided with a sewed slot for the reception of the upper lace curtain supporting arms 21 upon which the curtain may be gathered to form vertical gathers or pleats, the lower portion of each curtain being gathered between the duplicate portions 41 and 42 of the lower arms 40. The lace curtains 60 are so arranged as to meet at the center of the window along the center line of the window 61, thereby giving the appearance of a single curtain extending across the window. The curtains 60 being supported by the upper and lower curtain supporting arms are positively held in posi-

tion across the window between the upper and lower arms whereby they are positively held in extended position at all times between these points.

5 The drop curtains 61 are each provided, adjacent to the top thereof, with a sewed slot within which each supporting arm 22 is inserted, and a suitable strip of fabric 62 may be sewed on to one side of each drop 10 curtain near the lower end thereof to form a slot within which the lower drop curtain supporting arm 52 may be inserted. The drop curtains 61 are thus supported adjacent to the top and lower ends thereof and are 15 maintained in proper extended position between the upper and lower supporting arms, the drop curtains being gathered or pleated on the supporting arms if desired.

The valance 64 is divided at the center of 20 the window and is supported by the valance supporting arms 23 inserted in the sewed slots or the like formed in the upper edge portion of the valance. Thus the valance, lace curtains and drop curtains are all supported by the duplicate curtain supporting 25 structures located upon opposite sides of the frame and are capable of being turned into the position shown in front of the window or away from in front of the window 30 by rotating the shafts 4 which carry the curtain supporting arms.

The lower portions of the lace curtains 60 below the lower curtain supporting arms 40 and the lower portions of the drop curtain 35 61 below the curtain supporting arms 52 are unsupported, and in order to prevent these portions of the curtains from swaying and being blown into the room or out of the window I provide one or more cords 66 which 40 are passed over the upper edge of the curtains and extend downwardly on either side thereof, as shown in Fig. 1, the free ends of the cord on each side of the curtain terminating in weighted tassels 67 which present 45 an ornamented appearance and by their weight serve to hold the lower ends of the curtains from being blown away from in front of the window. With this form of holding means I may employ a clip 68 50 adapted to hold the cord in position and to fit over either the arm 21 or 22 to maintain each cord 66 in proper position relative to the curtain. The clip 68 is provided upon opposite sides with slots 69 entering from opposed edges through which the cord may pass so that that portion of the cord overlying the upper edge of the curtain is located under the central portion of the clip. The clip 68 is preferably made with 55 outturned lips 70 formed at the lowermost edge of each side, and a slot 71 is cut in each lip to receive the cord 66. The clips serve to retain the cords in proper position upon the upper curtain supporting arms 60 at all time.

In Figs. 9 and 10 I have shown a modified form of weighted cords for holding the lower edges of the curtains in place, wherein I employ hooks 72 to be passed through the curtain fabric above the upper curtain 70 supporting arms each of said hooks being provided with an eye 73 for the reception of a cord. In this form of the invention the cord 75 is passed through the eyes 73 of two hooks both located on one side of 75 the curtain so that both weighted ends of the cord extend downwardly and are located upon one side of the curtain.

In Fig. 7 I have shown a further modified form of the weighted cord wherein the 80 cord is made in the form of a loop sufficiently large to extend over the top of the upper curtain supporting arm and downwardly on each side below the curtain where a single weighted tassel 81 is attached to 85 the cord and the curtain thereby held against undue movement in either direction.

From the above description it will be seen that I have provided a curtain supporting 90 structure for positively supporting each curtain at points adjacent to the top and bottom parts thereof whereby the curtains may be turned into position in front of the window or away from in front of the window 95 as desired. The upper and lower curtain 100 supporting arms being adjustable on the shafts 4 may be adjusted vertically as desired to adapt the same to fit windows of different lengths or to compensate for shrinkage of the curtains. Moreover the entire curtain supporting structure may be bodily removed from the window or replaced thereon by withdrawing the reduced 105 portions 17 and 18 of the shaft 4 from the restricted openings 8 and 12 in the brackets 2 and 3 or pass them therethrough. The lower lace curtain supporting arm structure as shown in Fig. 12 is so constructed as to provide a means for supporting the curtains by engaging the same between two 110 members whereby the curtains may be readily secured in place or freed from engagement with the curtain supporting arm.

What I claim is:

1. A curtain supporting structure comprising a pair of separately positioned vertically aligned brackets, each provided with a bearing opening and a reduced lateral opening communicating therewith, a vertically positioned shaft provided with reduced portions bodily insertable by lateral movement or removable from said brackets, and upper and lower curtain supporting arms carried by said shaft. 115

2. A curtain supporting structure comprising a rotatable shaft, upper and lower curtain supporting arms carried by said shaft, said upper and lower curtain supporting arms being off-set horizontally whereby spaced curtains may be carried by said arms 120 125 130

and supported thereby at points adjacent to the top and bottom of said curtains to maintain the said curtains in spaced relation to each other throughout a substantial portion 5 of their extent.

3. A curtain supporting structure comprising a pair of separately positioned bearing brackets provided with vertically aligned bearings and restricted openings 10 communicating with said bearings, a shaft provided with reduced portions whereby said shaft may be laterally inserted in or removed from said bearings, and upper and lower supporting arms carried by said shaft.

4. A curtain supporting structure comprising a pair of bearing brackets provided with vertically aligned bearings and having restricted openings communicating with said bearings, a shaft provided with reduced 15 portions whereby said shaft may be laterally inserted in or removed from said bearings, and upper and lower supporting arms adjustably mounted on said shaft whereby said upper and lower supporting arms may be 20 secured to said shaft at varying distances 25 from each other.

5. In a curtain supporting structure, a pair of upper and lower curtain supporting arms vertically spaced from each other, said upper and lower arms being off-set horizontally from each other, and a valance supporting arm adjacent to said upper curtain supporting arms and off-set therefrom, a rotatable support common to all of said 30 arms, and means for retaining said support in a plurality of angularly adjusted positions.

6. The combination with a window frame 40 of curtains therefor comprising oppositely positioned vertically arranged draperies and a divided valance extending from either side of the frame to a point adjacent to the center of the window, and common means for supporting said curtains and valance.

7. The combination with a window frame 45 of curtains therefor comprising oppositely positioned vertically arranged draperies and a divided valance extending from either side of the frame to a point adjacent to the center of the window, and common means for supporting said curtains and valance comprising a rotatable shaft movable to bodily position said curtain and valance in front of the window or away from the front of the window.

8. In a curtain supporting structure, upper and lower bearing brackets, a shaft rotatably supported thereby, and a pair of upper and lower curtain supporting arms 55 carried by said shaft above and below said

upper and lower brackets respectively, said upper curtain supporting arms being off-set horizontally from each other and said lower curtain supporting arms being off-set horizontally from each other, for supporting 65 curtain members in off-set relation to each other and maintaining the same in extended position.

9. In a device of the character described, a curtain supporting arm comprising a 70 curved portion for surrounding a shaft, a straight portion extending from one side of said first named curved portion and merging into a second curved portion, a straight portion extending from the other side of 75 said first named curved portion, means for clamping said straight portions together to bind said first named curved portion securely to said shaft, and an extension member slidably supported by said curtain support- 80 ing arm to vary the effective length thereof.

10. A curtain supporting structure comprising a rotatable shaft provided with reduced portions, and a pair of vertically aligned brackets for supporting said shaft, 85 each of said brackets being provided with a bearing opening serving as a bearing for said shaft and having a restricted opening communicating with the bearing opening for admitting the reduced portions of said shaft 90 to the bearing opening, whereby said shaft may be positioned within or removed from said bearings by lateral movement of said shaft.

11. A curtain supporting structure comprising a rotatable shaft provided with reduced portions, a pair of vertically aligned brackets for supporting said shaft, each of said brackets being provided with a bearing 95 opening serving as a bearing for the shaft 100 and having a restricted opening communicating with the bearing opening for admitting the reduced portion of said shaft to the bearing opening, and upper and lower curtain supporting arms carried by said shaft 105 whereby that portion of the curtain intermediate said arms is maintained in extended position.

12. A curtain supporting structure comprising a rotatable shaft provided with reduced portions, and a pair of vertically aligned brackets for supporting said shaft, each of said brackets comprising a portion adapted to be secured to a window frame 110 and a free end bent to form a bearing for said shaft and a reduced opening communicating with said bearing.

In testimony whereof I have affixed my signature.

GEORGE W. DOVER.
